UNITED STATES PATENT OFFICE.

WILLIAM J. REGAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

DRAFT-RIGGING.

1,346,556.

Specification of Letters Patent.

Patented July 13, 1920.

Application filed August 28, 1919. Serial No. 320,452.

To all whom it may concern:

Be it known that I, WILLIAM J. REGAN, a citizen of the United States, residing at Pittsburgh, in the county of Allegheny and State of Pennsylvania, have invented certain new and useful Improvements in Draft-Rigging; and I do hereby declare the following to be a full, clear, and exact description of the invention, such as will enable others skilled in the art to which it appertains to make and use the same.

My invention relates to draft rigging which, while capable of general application to railway vehicles, is especially suitable for equipping cars such as are usually comprised in passenger trains. The primary object of the invention is to provide a simple, compact, durable and efficient device involving a few and easily assembled parts which as a whole constitute a draft rigging having centering mechanism serving normally to center the car coupler thereof in the longitudinal axis of the car. Generally stated, this object is accomplished by constructing the head and shank of the coupler so as to allow the laterally projecting spring boxes of the centering mechanism to be assembled in position on the coupler shank by inserting them through the coupler head and through the forward part of the shank, the latter being provided with oppositely disposed apertures through which the respective spring-boxes project and being formed with an interior cavity permitting the said boxes to be brought into alignment with the said apertures and in spaced relation to each other.

There are other features of invention, residing in particular combinations of elements and advantageous forms of parts, all as will hereinafter appear.

In the drawings chosen to illustrate the preferred form in which I contemplate applying my invention, the scope whereof is set forth in the claims,

Figure 1 is a plan view of a draft rigging embodying the invention, the rear part of the draft yoke being broken away, a portion of the car underframe being shown.

Fig. 2 is a side elevation of the construction shown in Fig. 1, the coupler carrier iron being in section.

Fig. 3 is a vertical longitudinal section of the coupler head and shank, showing the relation of the centering mechanism thereto.

Fig. 4 is a detail horizontal section of the

coupler, the coupler head being omitted and the section being taken through the center of the spring-boxes.

Fig. 5 is a section on the line 5—5, Fig. 2.

In the drawings, 1 indicates the coupler and 2 is a draft yoke. The coupler is pivotally connected to the car, preferably by pivotal connection with the yoke, so as to be capable of swinging laterally with respect thereto. The head 3 of the coupler may be, and preferably is, of the well known Master Car Builders' standard "D" coupler type, as illustrated in the drawings, involving the knuckle 4, lock 5, knuckle opening lever 6 and lock lifter 7, which latter is here shown as of the underneath type without, however, intending to exclude the use of the well-known overhead form of lifter if the constructor should desire to employ it.

The shank 8 of the coupler is hollow, its interior being in open communication with the interior of the coupler head 3 to which it is integrally united. To the rear of the junction of the shank and head the side walls of the shank diverge rearwardly, as at 9, and thereafter preferably converge or approach each other somewhat abruptly, thereby affording extended bearings or shoulders 10 for supporting the rear sides of the spring-boxes 11. In advance of the bearing shoulders 10 the inclined side walls 9 of the shank are respectively provided with oppositely disposed apertures 12 through which the outer ends of the corresponding spring-boxes project. The inclined or rearwardly flaring sides 9 of the coupler shank afford space facilitating the assembly of the spring boxes and the coupler shank without unduly enlarging said shank, and such construction also enables the shank when displaced to the limit of its lateral swing to have extended bearing contact with the center sills 13 of the car, thus preventing the distortion of the front ends of the sills that would be liable to occur if the sides of the coupler shank were made parallel.

The coupler is adapted to be pivotally connected to the railway vehicle, its shank being for this purpose preferably formed at its rear end with integral pivot lugs or trunnions 14 which are adapted to be pivotally connected to the forward end of the yoke 2, said yoke, when such form of pivotal connection is employed, being preferably provided with a lower integral shoulder 15 and an 110

upwardly movable block or shoulder 16 which normally engage the forward faces of the respective trunnions 14 to thereby detachably connect the coupler to the yoke.

- 5 The hollow spring-boxes 11 between which the transversely extending centering spring 17 is operatively interposed preferably are rectangular in cross-section and formed on opposite sides at their inner or adjacent ends 10 with shoulders or flanges 18 which, by engaging portions 19 and 20 of the coupler shank adjoining the apertures 12 through which the boxes project, serve to limit the extent to which the spring 17 may force the spring-boxes apart. One of the spring-boxes is preferably provided at its outer end with a removable threaded plug 21 which may be formed with a square opening 22 serving as a convenient means for receiving 15 a wrench or square bar for removing and replacing the plug. This construction permits the spring 17 and contained guide bar 23 to be readily put in position by inserting them through the opening in the spring-box, the 20 said opening being thereafter closed by screwing the plug 21 into place.

The interior of the shank 8 of the coupler is provided with transversely extending guide ribs or shoulders, 24 and 25 respectively, which engage the ends of the flanges 18 of the spring-boxes and thus form guides for maintaining the alinement of the boxes as they reciprocate toward or from each other on the bottom wall of the hollow shank 30 in the operation of compressing the spring 17 or of restoring the coupler to centralized position in the longitudinal axis of the car after it has been laterally displaced therefrom. The forward guide shoulder 24 is of 35 a height affording sufficient space between it and the opposite wall of the coupler shank to allow the spring-boxes 11 to pass when being brought to assembled position or being 40 disassembled from the shank.

45 As well shown in Fig. 2 the spring-boxes 11 are preferably so related to the coupler that the axis of the transverse centering spring 17 is below the longitudinal center line of the coupler shank 8, thus enabling 50 the pressure of the spring-boxes against the coupler when returning the latter to normal position to be exerted closer to the frictional surfaces of the coupler and carrier iron 26, which is of course desirable.

55 In assembling the coupler centering mechanism on the coupler the spring-boxes 11 are successively inserted into the interior of the coupler head 3, passed through the throat of the coupler into the interior of the coupler shank 8, and then pushed rearwardly and brought into assembled relation with their outer ends projecting outwardly through the corresponding apertures 12 in the side walls of the coupler shank. The spring 17 and 60 guide-bar 23 then may be put in position 65

through the opening in the outer end of one of the boxes, after which the threaded plug 21 is screwed into place, said plug preferably giving to the spring a slight initial compression.

70 I claim:

1. In mechanism of the character indicated, the combination with a coupler having a hollow integral shank provided upon opposite sides with apertures affording communication with the interior of said shank, of means for centralizing said shank with respect to the car, said means involving spring-boxes mounted on said shank and respectively projecting outwardly through said apertures, the hollow portion of said shank in advance of said spring-boxes constituting a passage which is open at the forward end of said shank and communicates with said apertures, and said passage being adapted to receive said spring-boxes at its forward end and to permit said boxes to be moved rearwardly therein and respectively entered in said apertures. 75

80 2. In mechanism of the character indicated, the combination with a coupler having an integral shank provided on opposite sides thereof with rearwardly diverging side walls having apertures therein, of means for centralizing said shank with respect to the car, said means involving spring-boxes mounted on said shank and respectively projecting through said apertures, said shank being formed with a passage extending rearwardly from the forward end of said shank 90 and communicating with said apertures, and said passage being adapted to receive said spring-boxes at its forward end and to permit said boxes to be moved rearwardly therein and respectively entered in said apertures. 95

100 3. In mechanism of the character indicated, the combination with a coupler having an integral shank and a head integrally united to said shank, said shank being provided on opposite sides with apertures 110 adapted to receive means for centralizing said coupler with respect to the car and being formed with an interior passage communicating with said apertures and with the interior of said coupler head, of means for centralizing said coupler with respect to the car, said means involving spring-boxes projecting outwardly through said apertures, said spring-boxes being adapted to be entered in said apertures by passing from the 115 interior of said coupler head through said passage. 120

125 4. In mechanism of the character indicated, the combination with a coupler having an integral shank provided with apertures on opposite sides thereof, of means for centralizing said shank with respect to the car, said means involving relatively movable spring-boxes provided with shoulders and mounted on said shank and respec- 130

tively projecting through said apertures, said shank having upon its interior transversely extending guide ribs or shoulders adapted to engage said shoulders of the 5 spring-boxes to maintain the alinement of said boxes and having an interior cavity extending rearwardly from the forward end of said shank and communicating with said apertures and adapted to permit the passage 10 of said spring-boxes.

5. In mechanism of the character indicated, the combination with a coupler having a head and integral shank which are rigidly united, of means mounted on said 15 shank for centralizing said coupler with respect to the car, said means involving relatively movable spring-boxes provided with shoulders adapted to engage said shank, and said shank being provided with rearwardly 20 diverging side walls having apertures there-in and being formed with an interior passage adapted to permit said spring-boxes to be entered in said apertures and being provided with shoulders adapted to engage and 25 guide said boxes.

6. In mechanism of the character indicated, the combination with a coupler having a head and integral hollow shank, of means mounted on said shank for centralizing said 30 coupler with respect to the car, said means involving spring boxes supported by and movable on the bottom wall of the coupler shank, and a spring having its ends housed in the spring boxes, said spring extending 35 transversely of said shank and having its axis below the longitudinal center line of said shank.

7. In mechanism of the character indi-

cated, the combination with a coupler having a head and integral hollow shank, of 40 means mounted on said shank for centralizing said coupler with respect to the car, and a carrier iron engaging the under side of said shank, said means for centralizing said coupler involving spring-boxes movably 45 mounted on said shank and projecting outwardly therefrom on opposite sides thereof and a spring extending transversely of the coupler shank and having its ends housed in the spring boxes, said spring-boxes being 50 supported by and movable on the bottom wall of the shank, said shank having guide shoulders for maintaining the alinement of the spring boxes.

8. In mechanism of the character indicated, the combination with a coupler having an integral shank provided upon opposite sides with apertures affording communication with the interior of said shank, of means for centralizing said shank with respect to the car, said means being mounted on said shank and involving shouldered spring-boxes respectively projecting outwardly through said apertures, said spring-boxes being open at their adjacent ends and 60 one of them being provided at its outer end with a removable member affording access to the interior of said box, and said shank being formed with an interior cavity extending rearwardly from its forward end and 65 communicating with said apertures and adapted to permit the passage of said spring-boxes.

In testimony whereof I affix my signature.

WILLIAM J. REGAN.
